ELECTRICAL CONNECTION

Earl P. Allabach, Upper Darby, Pa.

Application April 14, 1934, Serial No. 720,545

3 Claims. (Cl. 173—343)

This invention relates to electrical connections, and has for an object to provide improved means for making connections with a power circuit to a light, implement, or other current consuming device.

5 A further object of the invention is to provide a connection having improved means whereby the connection may be more easily and readily effected.

10 A further object of the invention is to provide means whereby the connection can be made with the inserted plug in any rotary position.

15 A further object of the invention is to provide improved means to enable the user to make the proper connections in the dark or positions of low visibility.

20 The invention, therefore, comprises a socket member of any approved general type having electrical contact members along the sides of the socket, with an electrically connected central pin 25 upstanding axially within the socket, and a plug member having a sleeve insertable into the socket, the sleeve having internal means for making an electrical connection with the pin and external electrical connection for making contact with the contact members at the sides of the socket.

25 The invention further includes the use of an insulating washer or guard which when the socket member is not in use covers one of the electrical terminals within the socket to prevent shock if a finger be inserted into the socket.

30 The drawing illustrates several embodiments of the invention and the views therein are as follows:

35 Figure 1 is a substantially diametrical sectional view through the connection,

Figure 2 is an end view of the plug,

Figure 3 is an end view of the socket,

40 Figure 4 is a substantially diametrical sectional view through a slightly different embodiment of the invention,

Figure 5 is a view partly in diametrical section and partly in elevation of a slightly different 45 modification of the socket member, and

Figure 6 is an end view of the socket member shown at Figure 5.

Like characters of reference indicate corresponding parts throughout the several views.

50 As usual, the present electrical connection comprises two parts, a socket member A and a plug member B. The socket member A is here represented as provided with a threaded exterior for coaction with an "Edison outlet". This socket member is shown merely by way of illustration

and intended to cover any and all types of socket members, whether fixed in an outlet box or removable therefrom, or otherwise used or seated.

As illustrated, the socket member comprises the body part 10 which is, of course, constructed of insulating material of any kind, as ordinarily employed in such work.

5 A central socket 11 is formed in this body 10 and along the sides of the central socket, contact strips 12 are positioned, extending as shown, through to the bottom of the body at 13 and arranged to make proper electrical contact as by union with the threaded shell 14.

10 Preferably, these contact strips 12 adjacent the upper and open end of the socket 11, will be 15 slightly bowed, as shown at 15, the utility of which will hereinafter more fully appear.

15 Inserted axially through the body 10 is a pin 16 which is provided with a head 17 for making contact within the usual "Edison outlet". Of 20 course, this latter feature will be eliminated in other types of socket members and will be replaced by such other devices, as are well-known in the art.

25 For coaction with the part A, the plug B comprises a body part 18 having a sleeve 19 extending axially therefrom. This sleeve 19 may, of course, be integral with the plug 18 or be otherwise attached. Spaced from the sleeve 19 by a furrow, as shown at 19a, is a rib 19b which engages the socket A. The sleeve 19 is provided with a circumferential contact band 20, which at one side is connected to or integral with a strip 21 which extends to the binding post 22. The sleeve 19 has a contact shell 23 located axially 30 therein, so proportioned as to make frictional engagement with the pin 16.

35 For this purpose the shell 23 is slotted longitudinally at a number of places, as indicated at 24, providing a limited amount of yielding and is 40 preferably also bevelled at its extremity as indicated at 25.

45 This shell 23 is continued by a strip 26 which makes engagement with the binding post 27. The binding posts 22 and 27 engage, respectively, 45 the wires 28 and 29 which are introduced into the plug through the petticoat 30.

50 A band 31 is shown encircling the sleeve 19, but this is merely a reinforcing band to prevent fracturing of the sleeve which, of course, being made of insulating material, is frangible to a greater or lesser degree.

55 As a modification there is shown at Figure 4 a pin 16', which is shorter than the pin shown at Figure 1.

This is for the reason of minimizing the danger of contact between that pin and side contacts in the socket. In this embodiment, also, the contact strips, instead of running along the inside 5 of the socket throughout, are embedded in the insulating material, as shown at 32, and the spring parts 33 are of greater curvature than the corresponding curves 15 shown at Figure 1.

Also, at Figure 4, the sleeve here shown as 34 10 is indicated as formed separate from the plug B. It is held in connection with the plug by frictional engagement wholly, or by the binding posts 27 and 22. In other respects the type shown at Figure 4 corresponds to Figure 1.

15 At Figure 5 an insulating washer or follower 35 is shown in the socket. This washer 35 is provided with a plurality of outstanding ears 36. At Figure 6 the number of ears are indicated as two, but it is to be understood that any number 20 is within the scope of the present invention.

These ears slide in grooves or guide passages 37 and a spring 38 is located within the socket surrounding the pin 16".

The washer is provided with a central opening 25 39 adapted to slide over the pin 16" when the sleeve of the plug is inserted. When the plug is removed the spring 38 tends to move the washer 35 to the outer limit of its movement and to wholly cover and protect the pin 16" so that it 30 will be difficult to make electrical contact between the spring members 33 and the pin 16".

All of the parts of the body, of the socket member, its pin, the plug and its sleeve, being coaxially arranged, it is obvious that the plug B 35 may be inserted into the socket in any rotary position. The socket being of considerable size, it is quite obvious that it will be easy to find the position for the sleeve and to make the necessary 40 electrical connections even in the dark or in positions of low visibility.

The arrangement of the device is such that seldom will identical parts engage with corresponding parts so that the corrosive action of arcing will be minimized and the life of the connection thereby prolonged.

45 Of course, the electrical connection described may be modified and changed in various ways without departing from the invention herein set forth and hereinafter claimed.

I claim:—

1. An electrical connection comprising a socket member having a contact spaced from the axis of the socket, a contact pin axially arranged within the socket, a plug member having a sleeve 5 adapted to be inserted into the socket with an annular furrow surrounding the sleeve producing a surrounding annular rib abutting and coinciding with the socket member and with an axial aperture for receiving the pin, a contact member within the sleeve, a second contact member external of the sleeve for making engagement with the first mentioned contact at the side of the socket, and conductor connections within the furrow connected to said contact members. 10

2. An electrical connection comprising a socket member having a socket therein, a contact pin of conductive material upstanding axially within the socket, a contact strip extending longitudinally of and projected into the socket, means to 20 make circuit connection with the pin and strip, a plug provided with a sleeve proportioned to enter the socket and having an axial recess, an annular rib surrounding and spaced from the sleeve, forming an annular furrow, a contact band 25 about the sleeve positioned intermediate its ends and to engage the inwardly projecting part of the strip of the socket only when the sleeve has been forced home, a slotted shell within the recess properly proportioned and positioned to make 30 clamping engagement upon the pin, and means within the furrow to make circuit connections with the band and shell.

3. An electrical connection comprising a socket member having a cylindrical socket therein with 35 radially offset longitudinally extending slots, an electrical contact member extending longitudinally along the inner surface of the socket, a conductor upstanding axially within the socket, a washer-shaped protector mounted within the 40 socket and having radially outstanding ears slideable in the slots, a spring tending to hold the protector in position to cover the end of the pin, and a plug having a cylindrical sleeve proportioned to enter the socket and depress the protector and make contact with both the pin and 45 the contact member in any rotary position.

EARL P. ALLABACH.
